CLAIM

The ornamental design for a pendant jewelry, as shown and described.

DESCRIPTION

FIG. 1.1 is a front view of a pendant jewelry showing our new design;

FIG. 1.2 is a back view thereof;

FIG. 1.3 is a right view thereof;

FIG. 1.4 is a left view thereof;

FIG. 1.5 is a bottom view thereof;

FIG. 1.6 is a top view thereof; and

FIG. 1.7 is a front left perspective view thereof.

The broken lines depict parts of the pendant jewelry that form no part of the claimed design.

1 Claim, 7 Drawing Sheets
